(57) **CLAIM**

The ornamental design for a motorcycle tail light as shown and described.

DESCRIPTION

FIG. 1 is a perspective view of the motorcycle tail light.

FIG. 2 is a front elevational view thereof.

FIG. 3 is a rear elevational view thereof.

FIG. 4 is a first side view thereof.

FIG. 5 is a second side view thereof, opposite the first side view.

FIG. 6 is a top side view thereof; and,

FIG. 7 is a bottom side view thereof.

The rear surface of the motorcycle tail light and boundary lines of the tail light lens shown in broken lines form no part of the claimed design.

1 Claim, 7 Drawing Sheets
